EJECT-INJECT LOCK MECHANISM

Richard W. Grant and Milton H. Rosengard, Los Angeles, Calif., assignors to Hughes Aircraft Company, Culver City, Calif., a corporation of Delaware

Application December 31, 1956, Serial No. 631,967

6 Claims. (Cl. 292—251)

The present arrangement relates generally to a locking arrangement and relates more particularly to a mechanism for use in moving a tray, drawer, door, chassis, or the like, into a final closed position and for thereafter securing the moved structure in such a closed position.

In many contemporary structures such as, for example, in electrical or electronic devices employing multiple contacts, extreme difficulty is experienced in the required forcing of many male and female contact structures into engagement with each other, due primarily to high frictional forces that are employed therewith. In structures such as, for example, computers and the like, it has become common practice to employ either multiple contact plugs or printed circuit edge contacts in association with a removable chassis or drawer. Such chassis are constructed in such a manner as to be removable for maintenance, repair or replacement of entire units or components thereof as may be necessary. The chassis are generally slid into suitable openings designed for reception thereof, with contacts protruding from rearward ends. These contacts are adapted to mate with other contacts carried by a rack or frame and means must thereafter be provided not only to lock these contacts in connected positions, but also to enable installation in a manner to overcome the high frictional forces without undue strain on individual components or the use of special tools or the like.

Accordingly, it is one important object of the invention to provide a novel eject-inject mechanism for use between relatively movable structures.

It is another important object of the invention to provide a lock mechanism having safety means as a portion thereof to prevent operation of eject-inject portions while the device is in a locked position.

A further object of the invention is to provide a rotationally operable cam means associated with a lock mechanism for applying axial force to a driver, chassis, or the like and thereafter to lock such chassis in position and/or remove said chassis as desired.

A still further important object of the invention is to provide a novel eject-inject locking mechanism that is exceptionally simple in construction, reliable and effective in use and relatively inexpensive in manufacture.

Other and further important objects of the invention will become apparent from the disclosures in the following detailed specification, appended claims and accompanying drawing, wherein:

Figure 1 is a side elevational view of the present eject-inject latching mechanism as shown sectionally in association with a typical installational situation;

Fig. 2 is a bottom plan view of the mechanism showing components in an injected locked position;

Fig. 3 is a view similar to Fig. 2 showing components in unlocked and partially ejected positions;

Fig. 4 is a reduced rear elevational view of the mechanism;

Fig. 5 is a transverse sectional view taken as indicated by the line 5—5, Fig. 3 and rotated 180°; and

2

Fig. 6 is a fragmentary sectional view showing details of the worm gear cam arrangement and locking device.

With reference to the drawing, wherein like reference numerals denote like components, the device hereof is shown as being carried by and operatively associated with a rack R, having a front panel P; a chassis C; and a mounting plate M. In the usual instance, the rack R is a portion of a stationary frame structure in which one or more of the chassis are slidably disposed. Various components, devices or associated structures are carried by and upwardly of the upper surface of the chassis C. The rack R is adapted to carry a strike plate 10 that is secured thereto by means of a plurality of rivets 11 or the like. The strike plate 10 has laterally extending flanges 12 that are disposed outwardly therefrom, remote from the contacting surface with the rack R. An upper planar surface 13 of the strike plate 10 is provided with a plurality of spaced semicircular quarter thread grooves 14, the purpose of which to be hereinafter more fully described.

As shown on the drawing, the latch portion of the present arrangement includes a housing 15 having a semicircular opening 16 therein. The housing further has lateral extending side portions 17 in which a pair of lateral grooves 18 are formed. The housing 15 also is provided with inwardly directed edges 20, the grooves 18 and the edges 20 being adapted for slidably receptive cooperation with the flanges 12 disposed from sides of the strike plate 10. The rearward portion of the housing 15 is cut away as at 21 for reception of a rear latch plate 22 that is secured to the housing by means of a pair of screws 23 which threadably engage the housing. As shown in Fig. 4, the rear latch plate is provided with a centrally disposed hexagonal aperture 24. A front latch plate 25 is mounted on the housing 15 on the side thereof remote from the latch plate 22, this front latch plate 25 having a centrally disposed annular aperture 26. The housing 15, together with the front latch plate 25, is adapted for attachment to a flange 27 of the chassis C and the front panel P by means of screws 28 that are disposed through the panel P and flange 27 and which threadably engage the housing 15, thus to secure the latch to the chassis-panel combination and the front latch plate 25 to the housing 15. For a purpose to be hereinafter more fully described, a guard member 30 is also secured to the panel P, portions of this guard member being disposed beneath the heads of screws 28. Additionally, the panel P is outwardly flanged as at 31 along a lower edge thereof.

With reference to Figs. 3, 5 and 6, a worm gear 32 is disposed within the semicircular opening 16 of the housing 15. The worm gear has an axially disposed hexagonal opening 33 therethrough for reception of a hexagonal portion 34 of a locking shaft indicated generally at 35. The locking shaft 35 has an enlarged outer end 36 that is adapted for slidable disposition within a recess 37 of a coupling member 38. The coupling member 38 has an outer end portion provided with wrench flats 40 and a cylindrical portion 41 that is adapted for pivotal disposition in the aperture 26 in the front latch plate 25. The coupling member 38 has an inner end thereof provided with an outwardly disposed flange 42, an inner face of which is adapted for engagement with an inner surface of the front latch plate 25, an outer face 43 of the coupling 38 being adapted for engagement with one end of the worm gear 32. To prevent rotation of the coupling 38 relative to the locking shaft 35, the coupling 38 is provided with a hexagonal aperture 44 that is adapted for axially slidable disposition about the hexagonal portion 34 of the locking shaft 35. As shown in Fig. 6, a compression spring 45 is disposed between an inner surface of the locking shaft head 36 and a base

of the recess 37. Additionally, an annular locking ring 46 is disposed about the wrench flat area of the coupling 38 and secured to the head portion 36 of the locking shaft 35 by means of a transversely disposed pin 47 that extends freely through elongated slots 48 in the coupling 38.

With further reference to Fig. 6, it is to be noted that the end of the locking shaft 35, remote from the head portion 36, is provided with a reduced diameter cylindrical portion 50 adjacent the hexagonal portion 34 and, on the outer end thereof with a hexagonal locking portion 51. The locking portion 51 is adapted for cooperation with the hexagonal aperture 24 in the rear latch plate 22. It may thus be seen that the worm gear 32 and coupling 38 are secured against rotation on the locking shaft 35 and that the shaft 35 is free to move axially within these members.

In operation of the present lock arrangement, the panel and chassis structure carrying the latch mechanism is inserted into a suitable opening in the rack R which has the strike plate 10 mounted thereon. Thereafter, through use of a suitable tool, such as an ordinary socket, the locking shaft 35 is moved axially with respect to the coupling 38 and the worm gear 32 and against the compression of the spring 45. Simultaneously, the hexagonal locking portion 51 of the shaft 35 is moved out of engagement with the hexagonal aperture 24 in the rear latch plate 22, whereby to dispose the cylindrical portion 50 of the shaft within the aperture 24. In this connection it is to be noted that when the portion 51 is disposed in the aperture 24, the coupling 38 and the worm gear 32 are held against rotation. It may be seen that axial force upon the ring 46 will act through the pin 47 to move the shaft 35 in an axial direction. After the components have been moved to the position shown in Fig. 3, the coupling 38 and worm gear 32 may be rotated by means of any suitable wrench applied to the wrench flats 40, thus to effect engagement between the worm gear 32 and the thread-like grooves 14 in the strike plate 10. This action serves to inject the panel carrying latch into the rack R under the force of the cam action between the worm gear 32 and thread-like grooves 14. When the components have reached the position shown in Fig. 2, force against the compression of the spring 45 may be relieved whereby again to dispose the hexagonal portion 51 of the shaft 35 in the aperture 24, thus to lock the worm gear 32 against rotation with respect to the strike plate 10 and prevent inadvertent removal of the chassis from the rack.

It is to be noted that the safety ring 46 serves effectively to cover exposed surfaces of the wrench flats 40, thus to prevent application of a wrench or socket to the coupling 38 until such time as the hexagonal portion 51 of the shaft 35 is moved out of engagement with the hexagonal aperture 24. Additionally, the guard 30, together with the panel flange 31, also serve to prevent application of a wrench type device to the coupling 38 inwardly of the safety ring 46. The latch structure is disengaged from the strike plate in a manner reverse of that described in connection with the injection operation, whereby to eject the chassis-panel combination from the rack R. It is to be noted that final movement upon injection and initial movement upon ejection may be accomplished with considerable force through use of the structure hereof and the cam action between the grooves 14 and the worm gear 32. The engagement of the flanges 12 of the strike plate 10 in the grooves 18 of the housing 15 serves to prevent lateral separation of the strike plate and worm gear.

Having thus described the invention and the present embodiment thereof, it is desired to emphasize the fact that many modifications may be resorted to in a manner limited only by a just interpretation of the following claims.

We claim:

1. An inject-eject latch mechanism comprising, in com-

bination: a strike plate adapted for disposition on a stationary structure; a latch carried by a movable structure; a plurality of grooves in said strike plate; a housing for said latch; a worm gear carried by said housing and adapted for cooperation with said grooves; tongue and groove means on said plate and said housing respectively for maintaining lateral engagement between said worm gear and said grooves; means for rotating said worm gear whereby to effect engagement between said gear and said grooves; and releasable means carried by said rotating means and cooperable with said housing for locking said gear against rotation.

2. An inject-eject latch mechanism comprising, in combination: a strike plate adapted for disposition on a stationary structure; a latch carried by a movable structure; a plurality of grooves in said strike plate; a housing for said latch; a worm gear carried by said housing and adapted for cooperation with said grooves; tongue and groove means on said plate and said housing respectively for maintaining lateral engagement between said worm gear and said grooves; means for rotating said worm gear whereby to effect engagement between said gear and said grooves; disengageable means carried by said rotating means and cooperable with said housing for locking said gear against rotation; and means for preventing rotation of said rotating means before disengagement of said locking means.

3. An inject-eject latch mechanism comprising, in combination: a strike plate adapted for fixed disposition on a stationary structure; a latch carried by a movable structure; a plurality of angularly disposed grooves in said strike plate; a housing for said latch; a worm gear carried by said housing and adapted for cooperation with said grooves; tongue and groove means respectively on said plate and said housing for maintaining lateral engagement between said worm gear and said grooves; tool attachment means for rotating said worm gear whereby to effect engagement between said gear and said grooves, said rotating means being axially slidably in said worm gear; disengageable means carried by said rotating means and cooperable with said housing for locking said gear against rotation; means for biasing said locking means toward a locked position; and means for preventing rotation of said rotating means before disengagement of said locking means.

4. A latching mechanism for use between a stationary frame and a movable element slidably disposed in said frame, comprising, in combination: a strike plate secured to said frame; a plurality of spaced angularly disposed thread-like grooves in an exposed surface of said plate; a latch housing secured to said movable element; a worm gear disposed in said housing, said gear being adapted for cooperable engagement with said grooves in said plate; a shaft carried by said housing and longitudinally slidably disposed in said gear; means for fixing said gear against rotation relative to said shaft; tongue and groove means respectively on said plate and said housing for maintaining said gear in lateral engagement with said grooves in said plate; a locking portion carried by one end of said shaft, said portion being hexagonal in cross-section and adapted for cooperation with a similarly shaped aperture in said housing, whereby to lock said shaft and said gear against rotation when disposed in the confines of said aperture; a coupling rotatably supported in said housing and disposed about another end of said shaft; means for securing said coupling against rotation relative to said shaft; and spring means disposed between said coupling and said shaft whereby to bias said shaft in a direction to effect disposition of said locking portion in said aperture.

5. A latching mechanism for use between a stationary frame and a movable element slidably disposed in said frame, comprising, in combination: a strike plate secured to said frame; a plurality of spaced angularly disposed quarter thread-like grooves in an exposed surface

of said plate; a latch housing secured to said movable element; a worm gear disposed in said housing, said gear being adapted for cooperable engagement with said grooves in said plate; a shaft carried by said housing and longitudinally slidably disposed in said gear; means for fixing said gear against rotation relative to said shaft; tongue and groove means respectively on said plate and said housing for maintaining said gear in lateral engagement with said grooves in said plate; a locking portion carried by one end of said shaft, said portion being hexagonal in cross-section and adapted for cooperation with a similarly shaped aperture in said housing, whereby to lock said shaft and said gear against rotation when disposed in the confines of said aperture; a coupling rotatably supported in said housing and disposed about another end of said shaft; means for securing said coupling against rotation relative to said shaft; spring means disposed between said coupling and said shaft whereby to bias said shaft in a direction to effect disposition of said locking portion in said aperture; and safety ring means disposed about said coupling and connected with said another end of said shaft for preventing application of tools to said coupling and rotation of said shaft and said gear prior to disengagement of said locking portion from said aperture.

6. A latching mechanism for use between a stationary frame and a movable element slidably disposed in said frame, comprising, in combination: a strike plate secured to said frame; a plurality of spaced angularly disposed quarter thread-like grooves in an exposed surface of said plate; a latch housing secured to said movable element; a worm gear disposed in said housing, said gear being adapted for cooperable engagement with said

grooves in said plate; a shaft carried by said housing and longitudinally slidably disposed in said gear; means for fixing said gear against rotation relative to said shaft; tongue and groove means respectively on said plate and said housing for maintaining said gear in lateral engagement with said grooves in said plate; a locking portion carried by one end of said shaft, said portion being hexagonal in cross-section and adapted for cooperation with a similarly shaped aperture in said housing, whereby to lock said shaft and said gear against rotation when disposed in the confines of said aperture; a coupling rotatably supported in said housing and disposed about another end of said shaft; a transversely disposed pin secured to said shaft and disposed in a slot in said coupling for securing said coupling against rotation relative to said shaft; spring means disposed between said coupling and said shaft whereby to bias said shaft in a direction to effect disposition of said locking portion in said aperture; and safety ring means disposed about said coupling and connected with said transversely disposed pin for preventing application of tools to said coupling and rotation of said shaft and said gear prior to disengagement of said locking portion from said aperture by longitudinal movement of said shaft against force of said spring means.
